UNITED STATES PATENT OFFICE.

PETER L. JENSEN, OF SAN FRANCISCO, CALIFORNIA, ASSIGNEE TO THE MAGNAVOX COMPANY, OF SAN FRANCISCO, CALIFORNIA, A CORPORATION OF CALIFORNIA.

TELEPHONE-TRANSMITTER.

1,332,873.

Specification of Letters Patent.

Patented Mar. 2, 1920.

Application filed January 2, 1918. Serial No. 210,081.

To all whom it may concern:

Be it known that I, PETER L. JENSEN, a citizen of the United States, residing at San Francisco, in the county of San Francisco and State of California, have invented certain new and useful Improvements in Telephone-Transmitters; and I do hereby declare the following to be a full, clear, and exact description of the same, reference being had to the accompanying drawings, forming part of this specification, and to the figures and letters of reference marked thereon.

In a previous application filed by myself and Pridham, Serial No. 187,361, there is illustrated and described a telephone transmitter designed and adapted for use in situations where it is subjected to extraneous sound waves as contradistinguished from vocal sound waves, one particular field of usefulness being in connection with aeroplane work in order to facilitate communication between the occupants of the plane. In designing the transmitter of said previous application, the construction adopted was one in which the diaphragm is exposed substantially equally on both sides to all extraneous sound waves, but so located with respect to the mouth of the user that vocal sounds to be transmitted impinge upon the diaphragm on one side only and that side is usually the side opposite to the electrode cell which functions to vary the current, in accordance with well known practice. In the device of said prior application, the transmitter is adapted to be held close to the face of the user with the diaphragm spaced a suitable distance in front of the user's mouth by an annular guard or support, and it is the object of the present invention to provide an improved construction and arrangement whereby the transmitter will be positioned and held with relation to the face and mouth of the user by face-engaging pads resting against the user's face at each side of the mouth only, thus leaving a completely free and unobstructed space at the top and bottom of the diaphragm and between said diaphragm and the user's face. In carrying the invention into practice, it is preferred to provide face-engaging pads which may be deformed to conform to the lines of contour or comfort for the particular user and the whole device is held in place by straps or

bands extending from the pads around the user's head or by other suitable fastening means attached to the pads themselves at points which will substantially insure the suspension of the diaphragm in proper relation to the mouth of the user to secure the most effective action, regardless of whether or not the user's head is in an upright or in an inclined position.

Referring to the accompanying drawings,—

Figure 1 is an elevation showing a transmitter embodying the present improvements held in place by a strap or band passing around the head.

Fig. 2 is a top plan view of the transmitter showing the face-engaging pad supporting plates without a covering thereon.

Fig. 3 is a side elevation of the structure shown in Fig. 2.

Fig. 4 is a perspective view of one of the pad-supporting plates, which under certain circumstances might serve as the pad itself.

The parts of the structure shown, which may be called the frame of the transmitter embody an annular or ring-like support A in which the diaphragm B is mounted in any ordinary or preferred manner, and a cross bar C spaced from and rigidly connected with the ring A by posts D. The electrode cell E is located between the bar C and diaphragm and the circuit terminal connections F extend to suitable binding posts f on the bar from whence the circuit connections lead to the electrode cell in the usual way. In accordance with the present invention the annular or ring-like frame A is provided with projections or standards G conveniently integral therewith and preferably flat or having flat faces for the reception of suitable guiding and clamping means adapted to co-operate with corresponding posts or lugs H formed on the pad plates I. A convenient and rigid form of connection consists in forming the lugs or posts H with slots h in which slots guide studs g and set screws g' are located. With this construction the distance between the pad plates I and the diaphragm in the ring A may be readily adjusted so as to position the diaphragm at the desired distance from the mouth of the user. The pad plates I are of such size and so spaced as to afford a comfortable bearing against the sides of the face

of the user, and at the same time when pressed against the face, to properly hold the diaphragm in place for use.

Inasmuch as it is a desideratum to avoid the transmission of sound waves to the diaphragm through any of the metal parts of the apparatus or to avoid setting up a resonant vibration due to non-vocal sound waves, it is preferred that the metal parts of the device should be made of a non-resonant metal, and for this reason as well as for the comfort of the user, the pad plates are preferably covered with nonheat-conducting, non-resonant material, such as animal fur, indicated at K in Fig. 1. Obviously, however, any nonheat-conducting material may be utilized for this purpose, especially any substance which will not tend to slip or slide when in contact with the skin.

The whole device is adapted to be held in place by supporting means coöperating with studs *i* located on the pad plates, preferably at points intermediate the centers and upper ends, and for coöperation with these studs there may be suitable connections with the helmet of the user, or an adjustable supporting strap, such as M, extending around the head may be provided.

The provision of separate and distinct face-engaging pads located at each side of the transmitter is highly advantageous for a number of reasons, but mainly because it leaves a free unobstructed opening up and down in front of the mouth of the user, with the result that the breath may escape freely, resulting in less difficulty from condensation or liability of moisture contacting with the parts of the transmitter, especially when flying at great altitudes and in extreme cold. Furthermore, it gives the user an opportunity to reach his mouth and nasal organs, should this be desirable or necessary, and it is especially important in that it permits extraneous sound waves to reach both the inner and outer sides of the diaphragm with practically equal facility and consequently such sound waves, acting on diametrically opposite sides of the diaphragm simultaneously, produce little or no effect which will interfere with the transmission of vocal sounds.

In order to permit the pads to be fashioned to fit the face of the particular user the pad plates are preferably formed of metal which may be bent and twisted into the desired shape, as, for example, relatively soft brass, care being taken, however, that the metal shall be sufficiently strong and

rigid to hold the transmitter against displacement by strains to which it may be subjected in use.

What is claimed is:

1. In a telephone transmitter, in which the diaphragm is exposed on opposite sides to non-vocal sound waves, of supporting means for positioning the transmitter with its diaphragm in position to receive the direct impact of vocal sound waves on one side only, embodying independent face-engaging pads spaced from the edges of the diaphragm and from each other, and means for holding said pads in position against the face of the user with the diaphragm in front of the mouth. 65

2. In a telephone transmitter of the character specified in claim 1, face engaging pads embodying deformable metal plates adapted to be bent to conform to the face of the user. 70

3. In a telephone transmitter of the character specified in claim 1, face engaging pads embodying non-resonant covering material adapted to rest against the face of the user. 75

4. In a telephone transmitter of the character specified in claim 1, laterally spaced face engaging pads, and posts connecting said pads and transmitter, whereby a clear space is provided above and below the mouth of the user. 80

5. In a telephone transmitter, a frame, a transmitter diaphragm supported in said frame and exposed on opposite sides equally to non-vocal sounds, adjustable posts carried by the frame, face-engaging pads carried by the posts in laterally spaced relation and supporting strap connections with the pads for retaining the pads in contact with the face of the user and the diaphragm in front of the user's mouth in position to receive vocal sounds directly on one side. 90

6. In a telephone transmitter, a circular frame having posts projecting therefrom on one side, a diaphragm mounted in the frame and freely exposed on both sides to sound vibrations, separate face engaging pads adjustably mounted one on each post for location a greater or less distance from the plane of the diaphragm, means for fastening said pads in adjusted position, and means for holding the pads against the face of the user with the diaphragm in position to receive vocal sounds on one side only and with an unobstructed space at the top and bottom of the diaphragm. 100

PETER L. JENSEN.
